FIGURE 6 is a fragmentary view of the waist portion of the trousers showing the waist band and adjoining area of the leg portion in the non-extended position; and

The characteristic feature of the design resides in the provision of alternate sections which are reversely pleated with the ridges of one pleated section aligning with the valleys of the next adjacent section for presenting a puckering line of demarcation to give a horizontal striped effect to the trousers as shown in full lines.

I claim:

The design for pleated trousers, as shown and described.
